UNITED STATES PATENT OFFICE.

JOSEPH FREDERICK SAUER, OF CHICO, CALIFORNIA.

ENGINE-TIME REGISTER.

Application filed April 6, 1920. Serial No. 371,660.

To all whom it may concern:

Be it known that I, JOSEPH FREDERICK SAUER, a citizen of the United States, residing at Chico, in the county of Butte and State of California, have invented a new and useful Engine-Time Register, of which the following is a specification.

My invention relates to a new and original engine time indicator, which is operated by the compression and vacuum created in a cylinder of an engine to which it is attached, and is composed of a rod or shaft used as an indicator, attached to a plunger which moves past a pressure release port in a cylinder as pressure is applied and returns as pressure subsides; and the objects of my invention are, first, to save time; second to simplify engine timing, especially for the repairman; third, to overcome guess work 20 without having to tear engine apart.

I attain these objects by the mechanisms illustrated in the accompanying drawings, in which—

Fig. 1 is a vertical section of the entire machine; Fig. 2 an external view; Fig. 3 top view; Fig. 4 bottom view; Fig. 5 a group of the internal mechanisms in detail.

Similar numerals refer to similar parts throughout the several views.

30 Hexagon 1, body of cylinder 2, $\frac{5}{8}$ inch spark plug hole fitting 3, and $\frac{1}{2}$ inch spark plug hole fitting 4, constitute the outside walls of the mechanism; the combination 3 and 4 may be changed to suit different conditions and objects to which the machine 35 may be attached.

The pressure, created in the cylinder of the engine during compression stroke by short movements of the piston, enters 40 through passage 5 forcing plunger 6 beyond exhaust port 7 in cylinder 8. Plunger rod 9 attached to previously mentioned plunger 6, and to indicator 10 goes through and is guided by plug 11.

45 As soon as the piston of the engine stops moving and the pressure subsides, spring 12, guided by plunger stop 13, forces plunger 6 back again beyond exhaust port 7 to its original position where it rests balanced between 50 spring 12 and spring 14. Plunger 6 alternates back and forth in the above described manner as often as the piston of engine is moved and stopped, until the said piston arrives at dead center or neutral point between 55 compression stroke and power stroke.

At this point plunger 6 remains still, and balanced between spring 12 and spring 14 as above described, thereby automatically indicating the dead center (usually called the upper dead center on vertical engines) of the compression stroke of the engine, which is the time the ignition is usually set to occur. Immediately as the piston of the engine moves to either side of dead center a vacuum is created which draws plunger 6 towards lower plunger stop and spring guide 15; thus each position of the piston of the engine affirms the registration caused on the indicator by the other positions. Port 16 releases any pressure or vacuum on back side of plunger 6, when moving back and forth, thus allowing perfect freedom of motion. This mechanism will register every cycle of the piston directly or indirectly. Spark plug hole fittings 3 and 4 may be changed to 70 suit any other connection or fitting as conditions require.

As often as vacuum is applied and released plunger 6 moves back and forth in the same manner as when pressure is applied to it and released, but in the opposite direction.

As the plunger moves back and forth very quickly due to the spring action on both sides of the same, the movement of the plunger will be heard very distinctly, as the plunger makes a noise when striking the upper and lower stops 13 and 15, and there is a peculiar sound given out when the air rushes out of the ports.

I claim:

1. An engine time register comprising a casing having communication with the cylinder of the engine, said casing provided with pressure and vacuum release ports, a movable plunger in said casing balancing means on opposite sides of said plunger, stop means for the lower end of said plunger, a visual signal element extending outwardly from the casing and from the upper end of 95 said plunger, and stop means for the upper end of the plunger.

2. An engine time register comprising a casing adapted to be removably applied to an engine cylinder and having an axial bore 105 communicating with the working chamber of the engine cylinder, a plunger having a sliding fit in said bore, pressure and vacuum release ports controlled by said plunger, balance springs acting on opposing ends of said 110

plunger, and a visual signal carried by said plunger and extending outwardly through said bore.

3. An engine time register comprising a casing adapted to be applied to the spark plug opening of an internal combustion engine, said casing having an axial bore from its inner to its outer end the inner end and communicating with the working chamber of the engine at its inner end, a plunger having a sliding fit in said bore, a visual signal staff extending from the outer end of said plunger through said bore to the exterior of the casing, lateral pressure and vacuum release ports communicating with said bore, balancing springs engaging the opposite ends of said plunger, and inner and outer stops for said plunger in the said bore.

4. An engine time register comprising a casing adapted to be removably applied to the spark plug opening of an internal combustion engine, a visual signal element slidably mounted in said casing and extending exteriorly thereof, means for causing movement of said signal element by pressure and vacuum within said casing acting on said signal element, and balancing means within said casing when the engine is on upper or lower dead center.

5. An engine time register comprising a casing adapted to be removably applied to the spark plug opening of an internal combustion engine, a visual and audible signal element movably mounted in said casing and extending exteriorly thereof, means for causing movement of said signal element by pressure and vacuum within said casing acting on said signal element, means for releasing pressure within said casing, and balancing means within said casing when the engine is at upper or lower dead center.

6. An engine time register comprising a casing adapted to be removably applied to the spark plug opening of an internal combustion engine, a signal element movably mounted in said casing, means for causing movement of said signal element by pressure or vacuum within said casing acting on said signal element, means for releasing pressure or vacuum within said casing, and balancing means within said casing when pressure or vacuum is not applied.

7. An engine time register comprising a casing adapted to be removably applied to the spark plug opening of an internal combustion engine, a signal element movably connected with said casing and means for causing movement of the signal element by pressure or vacuum within the working cylinder of said engine.

8. An engine time register comprising a casing adapted to be removably applied to the spark plug opening of an internal combustion engine, and a signal element movably mounted in said casing, means asso-

ciated with said casing for causing said movement of said signal element by pressure and vacuum within the casing and means for releasing pressure and vacuum within said casing.

9. An engine time register comprising a casing connected with and communicating with the cylinder of an internal combustion engine, a signal element movably mounted in said casing, a pressure chamber at one side of said mounting, a pressure and vacuum chamber at the other side of said signal element, and means for releasing pressure or vacuum in said chambers.

10. The combination with an internal combustion engine cylinder, of an engine time register comprising a casing having a central bore communicating with said cylinder and adapted to receive pressure therefrom, a signal element movably mounted in said bore, and means within said bore for releasing the pressure whereby the movable signal element is caused to function.

11. As a new article of manufacture, an engine time register comprising a casing adapted to be removably applied to an internal combustion engine cylinder, and having a bore communicating with said cylinder, a movable signal element associated with said bore, and means mounted in said bore and coacting with the signal element to cause the same to indicate pressure or vacuum in the engine cylinder, both visually and audibly.

12. An engine time register adapted to be removably applied to an internal combustion engine cylinder, and comprising a casing having a bore communicating with said cylinder, a signal element movably carried by said casing, and means movably mounted in said bore and coacting with said signal element to give a visual and an audible indication by release of pressure within said engine cylinder.

13. As a new article of manufacture, an engine time register comprising a bored base member adapted to be removably applied to an internal combustion engine cylinder, a movable signal element associated with said bored base member, means coacting with said signal element for visually and audibly indicating the existence of pressure and vacuum in the cylinder, and independent pressure and vacuum release means interposed between the bore of said base member and the atmosphere.

14. An engine time register comprising a casing adapted to be removably applied to the spark plug opening of an internal combustion engine, a visual signal element movably mounted in said casing and extending exteriorly thereof, means for causing movement of said signal element by pressure and vacuum within said casing acting on said signal element, means for releasing pressure

within said casing and balancing means within said casing when the engine is on upper or lower dead center.

15. An engine time register comprising a casing adapted to be removably applied to the spark plug opening of an internal combustion engine, a signal element movably connected with said casing, means for causing movement of the signal element by pressure within the working cylinder of the engine, and means for releasing pressure within said casing, and balancing means within the casing when pressure or vacuum is not applied.

16. An engine time register comprising a casing adapted to be removably applied to the spark plug opening of an internal combustion engine, movable signal means for indicating both pressure and vacuum, and automatic pressure release means interposed between the casing and the atmosphere.

17. An engine time register comprising a bored base member adapted to be fitted into the cylinder head of an internal combustion engine, a movable signal member mounted in said base member, means actuated by pressure or vacuum in the bore for moving the signal member in any direction, means for releasing pressure or vacuum and balancing means operable when pressure or vacuum is not applied.

18. An engine time register comprising a

bored base member adapted to be fitted into the cylinder head of an internal combustion engine, a movable signal member 35 mounted in said base member, and means actuated by pressure or vacuum in the bore for moving the signal member in opposite directions respectively, means for releasing pressure or vacuum and means for normally 40 maintaining the signal member in a neutral position.

19. An engine time register comprising a bored base member adapted to be fitted into the cylinder head of an internal combustion 45 engine, a movable signal member mounted in said base member, means for normally maintaining the signal member in a neutral position, means actuated by pressure or vacuum for moving the signal member, and 50 pressure release means.

20. An engine time register, comprising a bored base member adapted to be fitted into an internal combustion engine cylinder-head, a movable signal member, means for 55 normally maintaining the signal member in a neutral position, means actuated by pressure or vacuum in the bore for moving the signal member in opposite directions with respect to the neutral position, and pressure 60 release means interposed between the bore and the atmosphere.

JOSEPH FREDERICK SAUER.
